5 Sheets-Sheet 4

A detailed technical line drawing of a mechanical assembly, labeled "Fig. 7." in the top left corner. The drawing shows a complex arrangement of mechanical parts, including a main frame, various shafts, bearings, and a large gear assembly. Numerous parts are labeled with numbers, such as 49, 100, 117, 64, 90, 116, 59, 111, 70, 71, 68, 23, 109, 101, 93, 113, 42, 112, 114, 66, 117, 84, 87, 24, 108, 104, 103, 106, 97, 99, 95, 94, 96, 99, 86, 85, 84, 82, 42, 84, 85, and 87. The drawing uses fine lines and cross-hatching to indicate different materials and assembly details.

STRING CLOSURE AFFIXING MACHINE

Stanley Kilinski, Brooklyn, N. Y., assignor to Baltimore Paper Company, Kansas City, Mo., a corporation of Missouri

Application October 12, 1944, Serial No. 558,443

10 Claims. (Cl. 93—1)

1

This invention relates to machines for attaching button and string fastenings to wrappers and similar articles.

In machines for attaching button and string fastenings, a paper or fiber button is spaced from the wrapper or other sheet material to which it is to be attached by a washer; and the button and washer are secured in place by means of an eyelet or grommet which is used also to anchor one end of a string. On articles having double button and string fastenings, the string wraps around the second button on another part of the article and is usually wrapped back and forth between the two buttons. On single button fastenings, the string passes around the package and the free end is wrapped around the button after being pulled tight around the package.

It is an object of this invention to provide an improved machine of the character described, and more particularly to provide a machine that will connect different lengths of string to the button. The string is supplied from a spool or other source by a threader that moves the end of the string into position to be gripped under the button when the eyelet or grommet is secured in place. The threader then moves away and measures out a predetermined length of string which is automatically cut off and the operation repeated for the next button fastening.

In machines of the prior art the string was always cut to the same length by shears which were located in a fixed position on the machine. One feature of this invention relates to a construction by which the shears for cutting the string are always at the same location on the machine, but the length of string between the eyelet connecting mechanism and the shears can be quickly and conveniently changed over a wide range. On packages such as are used for wrapping remnants in department stores, the length of string desired may be relatively short, but on moving picture reels that have a paper strip wound around and outside for protection, a very long string is necessary. This machine can be used for different types of wrapping having various lengths of string without changing any of the mechanism other than guide members that determine the course of the string after it leaves the threader.

Another object of the invention is to provide a machine of the character indicated with a threader that moves along a curved path. Such a course for the threads makes it possible to conveniently control the length of string that is pulled out from the threader by locating abutments inside of the curve along which the end of

2

the threader travels. The tendency of the string is to move inward and form a chord across the arc along which the end of the threader travels. Abutment means located just inside this arc or curved path can be used to break up the course of the string into any number of short chords the total combined lengths of which approximate the length of the curved path along which the threader moves.

10 Another feature of the invention relates to simple cam-operated mechanism for causing a threader to move along a straight line or an arc having a very long radius of curvature during the latter part of the travel of the threader. This permits the threader to move the string into position for cooperation with the eyelet or grommet setting mechanism along a substantially straight path even though the course of the threader as it measures out the string is along a path of comparatively short radius of curvature.

15 Other objects, features and advantages of the invention will appear or be pointed out as the specification proceeds.

20 In the drawings, forming a part hereof, in which like reference characters indicate corresponding parts in all the views,

25 Figure 1 is a perspective view of a machine made in accordance with this invention for attaching button and string fastenings with strings of different length.

30 Figure 2 is an enlarged view, partly in section, of the mechanism for attaching the button and string to a wrapper, envelope, or other article by means of an eyelet or grommet.

35 Figure 3 is an elevation of a portion of the mechanism illustrated in Figure 2, but in a different position.

40 Figure 4 is a view similar to Figure 3 but with a gear shown in section and with the string engaging member in a different position.

45 Figure 5 is a front elevation of the gear and cam mechanism of Figures 3 and 4 when viewed from the right.

Figure 6 is a perspective view of the back of the machine shown in Figure 1.

50 Figure 7 is an enlarged fragmentary perspective view of a portion of the mechanism shown in Figure 6 but viewed from a different angle.

Figure 8 is a fragmentary perspective view illustrating the cam mechanism for controlling the final part of the movement of the threader.

55 Figure 9 is an enlarged perspective view of a portion of the structure shown in Figure 6.

The machine shown in Figure 1 includes various roll mechanisms 20 for feeding strips from which

buttons and washers are punched automatically in a position to cooperate with eyelet or grommet attaching mechanism designated generally by the reference character 21. The eyelets are fed from a container 22 having feed mechanism connected with a drive shaft of the machine by a belt 23.

Power for operating the machine is supplied to a drive shaft 24 through a pulley 25. A crank-arm 26 is connected to one end of a shaft 27 which is driven from the pulley 25 through bevel gears 28, one of which is keyed to the drive shaft 24. The crank-arm 26 is connected by a link 30 to a block 31 fastened to a die 32 which slides in bearings 33.

The construction of the apparatus for punching the buttons from strips of paper or other sheet material, and for feeding these strips, will not be described since it is not necessary for a complete understanding of this invention. Such apparatus is illustrated in Trenchard Patent No. 1,522,760, issued January 13, 1925. This invention is an improvement on the machine illustrated in the Trenchard patent, and in the earlier Trenchard Patent No. 1,258,829, issued March 12, 1918.

The portion of these earlier machines that is important in connection with the present invention is illustrated in detail in Figures 2 to 5. A die 34 cooperates with the die 32 and is operated from the main drive shaft 24 through mechanism similar to the parts 26-33 of Figure 1. These mechanisms cause the dies 34 and 32 to be brought together once for each revolution of the main shaft 24. Further means are provided for automatically feeding an eyelet 36 to the machine and positioning the eyelet upon a slidable pin 37 which is loosely mounted in a centrally bored hole in the die 32. The pin 37 is held, when uncontrolled, in the extended position shown in Figure 2, by a spring 38. For the purpose of this application, the eyelet feeding and button and washer forming means may be disregarded and attention confined to the means for adding the string to the complete combination of button, washer and wrapper, or other sheet material to which the button and string fastening is to be applied.

The attachment of the string to the wrapper or other sheet material, may be effected by looping the string around the pin 37 before the dies have been brought together to upset the eyelet. It will readily be observed how this is effected when the reinforcing washer 39 is placed upon the die 34, as shown in Figure 2, and the eyelet 36 and fastening washer 40 are placed upon the pin 37 of the die 32 before the dies are caused to approach each other. If the wrapper or other sheet member be then inserted between the dies, and the dies be caused to come together, then the string 42 which has been previously wound upon the pin 37 is caught between the sheet material and the reinforcing washer 40 and firmly held there by the flanges of the eyelet 36.

The means for wrapping the string 42 around the pin 37 comprise a hollow gear 46 mounted in a suitable housing and rotated concentrically about the pin 37. The opening through the gear 46 is of sufficient size to permit the die 32 to pass therethrough. This gear is rotated from a jack shaft 35 by a gear 47 which drives the hollow gear 46 through an idler, not illustrated, and the gears are preferably of such size that the hollow gear 46 rotates at a greater angular speed than the jack shaft 35. The gear 46, with its associated parts, will hereinafter be termed the "looper," and the looper preferably makes four

revolutions to one revolution of the jack shaft 35. Power is supplied to the jack shaft 35 by a chain drive 48 from the main drive shaft 23 (Figure 6) at a one-to-one speed ratio.

Referring again to Figures 2-5, means are provided on the gear 46 for grasping the end of the string 42. This string-grasping means comprises a substantially U-shaped member 49 which is urged against the recessed face of the gear 46 by springs 50 (Figure 4), but which is adapted to be extended from the face of the gear in the proper moment when it is to grasp the end of the string 42.

The parallel sides of this U-shaped member 49 extends through the gear 46 and are fixed to a ring 51 that has a cam face 52 on its side away from the gear 46. The ring 51 is held away from the gear 46 by the springs 50 and its movement is limited by the U-shaped member 49 which can be moved no further by the springs after it enters the recess in the face of gear 46, as shown in Figure 4. When the end of the string is placed between the U-shaped member 49 and the left hand face of the gear 46, and the member 49 has moved in against the face of the gear, the string is firmly gripped.

Means are provided to control the movement of the U-shaped member 49 into and out of contact with the side of the gear 46 for the purpose of threading the string 42 into position to be gripped by member 49. This means comprises an abutment 54 that is connected with the end of a lever 55. The lever 55 contacts with a cam 56 on the jack shaft 35. This cam 56 causes the abutment 54 to move into the path of the cam face 52 of the ring 51 once for every revolution of the jack shaft 35. This means that the abutment 54 moves into the path of the cam face 52 once in every four revolutions of the looper. The abutment 54 causes the cam face 52 to displace the ring 51 toward the left in Figures 2 to 4, and to move the U-shaped member 49 into the position shown in Figure 2 so that a device comprising a threader 59 can insert the end of the string 42 into the space between the member 49 and the left hand face of the hollow gear 46.

After the end of the string 42 has been gripped by the looper, the threader 59 moves away from the looper mechanism and thread is drawn out through a guide 60 from a spool of string 62, shown in Figure 6.

The threader has a head to which the leader line of reference character 59 leads in the various figures of the drawing, and has a radially extending portion or support comprising an arm 64 with a hub 65 secured to an oscillating shaft 66. The head 59 is located on one side of the arm 64 and is thus offset from the arm 64 in a direction parallel to the axis of shaft 66. The oscillating shaft 66 is rocked back and forth by a pinion 68 (Figure 7) that meshes with a rack 70 which slides in a bearing block 71 (Figure 6) mounted on a bracket 72 which is free to oscillate on the shaft 66.

The rack bar 70 is connected at its upper end to a crank pin 74 secured to a crank 75 but adjustable lengthwise along a slot in the crank 75 for regulating the length of the stroke of the rack bar 70. The crank 75 is rigidly secured to one end of the main drive shaft 24 which is driven by the pulley 25. It will be evident that this mechanism causes the threader arm 64 to rotate through an angle and back again to its starting position during each revolution of the drive shaft 24.

Figure 7 shows a rear view of the machine with the threader arm 64 at its limit of movement away from the looper mechanism. In this view the looper mechanism is not shown, but the approximate position of that end of the string that is held by the looper is indicated by the reference character 49. The threader head 59 from which the string 42 extends is positioned beyond the cutter means or shears 90 that sever the string.

As the threader arm 64 moves the threader head 59 along a circular course about the axis of the shaft 66 as a center, the string 42 will tend to move inward and form a chord of the arcuate threader path unless the string strikes against obstructions that prevent it from moving inward. If enough such obstructions or abutments are provided just inside the path of movement of the threader head 59, the course of the string will comprise a series of short chords that will approximate the circular path of the threader head in total length.

A plate 82, which is preferably circular, is rigidly fastened to the frame of the machine, and there are radial arms 84 attached to the plate 82 by bolts 85. These bolts thread into openings in the plate 82. The arms 84 are preferably slotted so that they can be adjusted lengthwise. If a longer adjustment is required than can be obtained from the slot, the bolts 85 can be inserted in holes 86 nearer the center of the plate 82.

At the outer ends of the arms 84 there are abutments comprising pins 87 that extend out from the arms 84 far enough to contact the string 42 when it moves inward from the circular path traversed by the head 59 of the threader. When it is desired to have a long length of string, a large number of arms 84 are used and they are adjusted to extend far enough out from the plate 82 so that the abutments or pins 87 are on the inside of the curved path followed by the threader head 59 and as close as possible to the path without actually obstructing the movement of the threader head. This condition is shown in Figure 6 which illustrates the machine adjusted to measure out the longest length of string possible. The way in which the length of string is increased by use of more of the arms 84 is brought out graphically in Figure 9 where the greater string length obtained by using three more arms 84 is indicated in dotted lines.

When a shorter length of string is wanted, the arms 84 are moved inward to decrease their radial extent, or if a still shorter length of string is wanted, some or most of the arms 84 are removed from the machine. Figure 9 shows the length of string that will be obtained with only two of the arms 84 attached to the plate 82. In the particular machine illustrated, the short bottom arm 84 is always used in order to prevent the initial run of string from the looper member 49 from striking against other parts of the mechanism under the machine. At least one other arm 84 near the cutter or shear mechanism 90 is desirable in order to have the final run of string enter the shear mechanism 90 at the proper angle. With just two arms 84 in the location shown in Figure 7, the machine is adjusted to cut one of the shortest lengths of string. The specific structure illustrated in the drawing can be adjusted to cut string of any length from 30 to 54 inches in length, but it will be evident that other embodiments of the invention can be constructed to provide string lengths within different ranges.

The shears 90 that cut the string are best shown in Figure 7. They include a lower blade 92 that is rigidly secured to a head 93. This head is fastened to an arm 94 by screws 95 that extend through a slot so as to permit adjustment of the length of the shears. The arm 94 has a clamp 96 at its lower end and is fastened to a square bar 97 by this clamp 96.

The bar 97 has cylindrical end portions in bearings 99 that are connected to the stationary frame of the machine. The bar 97 is rocked in these bearings by a crank 100 fastened to the upper end of the bar 97. This crank 100 has a pin 101 connected by a link 102 with a lever 103 that rocks about a fulcrum 104 supported from the main frame. A spring 106 at the rearward end of the lever 103 is anchored to the main frame by a stud 107 and holds a roller 108 at the forward end of the lever 103 in contact with a cam 109 in the shaft 24.

The shears 90 include also a movable blade 111 that rocks on a pivot 112. The blade 111 is held in an open position, as shown in Figure 7, by a spring 113. There is an integral extension 114 that projects downward from the movable blade 111 into a position adjacent an abutment 116. Brackets 117 secure the abutment 116 to the frame of the machine.

Each revolution of the cam 109 rocks the square bar 97 and moves the shears 90 toward the right in Figure 7. This movement causes the extension 114 to strike the abutment 116 and move the upper blade 111 downward to close the shears 90 and clip the string 42 at a point that leaves just the right amount of string extending from the threader for cooperation with the looper at the end of the return movement of the threader.

Figures 8 and 9 show the threader construction. The head 59 is connected to the arm 64 by a pivot 119. The rearward end of the head 59 is connected by a link 121 to one end of a rocker arm 122 that oscillates about a pivot 123 carried by the arm 64 near its hub. A cam follower comprising a roller 125 on one end of the rocker arm 122 rides up on a fixed cam 126 as the threader approaches the looper mechanism. The cam 126 is connected with the main frame of the machine.

As the roller 125 moves up on the cam 126, the arm 122 is rocked clockwise in Figure 8, and this motion is transmitted through the link 121 to the threader head 59. The rocking movement of the head 59 as its pivot 119 swings in an arc causes the upper end of the head 59, from which the string extends, to move along a straight line, or curve having a long radius of curvature, depending upon the shape of the cam 126. A spring 128 tensioned between the end of the arm 64 and the rearward portion of the head 59 moves the rocker arm 122 and head 59 back into their original position as the arm 64 swings away from the looper mechanism and the cam follower 125 leaves the cam 126.

This cam-actuated movement of the head 59 makes it possible to have the end of the string enter the looper along a straight or substantially straight line without requiring that the arm 64 be of great length. In the illustrated embodiment of the invention, the arm 64 is short enough to swing under a machine that has a low frame; the type of machine with which the operator is seated while at work.

The course of the string is shown in Figures 6 and 8. From the spool 62 the string 42 passes up behind the plate 82 and comes through an

opening 130 in the center of the plate. The string then passes through a tubular guide 131 (Figure 8) that extends through the threader arm 64. The tubular guide 131 extends out far enough to permit the string 42 to pass in front of the rocker arm 122. A short distance beyond the tubular guide 131, the string enters another tubular guide 132 which extends substantially the entire length of the threader arm 64. At the outer end of the threader arm the string 42 passes from the guide 132 to the threader head 59 in which it is gripped between the side of the threader head 59 and a spring 134. This spring and the side of the threader head comprise the guide 60.

The preferred embodiment of the invention has been illustrated and described, but various changes and modifications can be made, and some features of the invention can be used without others without departing from the invention as defined in the claims.

What is claimed is:

1. In a machine for attaching a string to a sheet article, looper apparatus for holding an end of the string, fastening means for securing the end of the string to the article at a predetermined location, a threader that moves toward the looper to deliver the end of the string and then away from the looper to draw out a length of string, said threader comprising a radially-extending portion and a head that moves along a curved path and that is offset from the radially-extending portion in a direction at an angle to the plane of said curved path, string-abutment means on the inside of the curved path of the threader head and in position to contact the string as said string moves inward as a chord of the curved path, and a shear for cutting the string.

2. Apparatus including in combination fastening means for connecting an end of a string with a sheet article, a threader including a support and a head that is offset from the support and that moves along a curved path to deliver an end of string to the fastening means and then away from said fastening means along the curved path to draw out a length of string, an abutment on the inside of the curved path that prevents the string from maintaining a straight run from the fastening means to the threader head as the threader head moves away from the fastening means, and a support on which the abutment is adjustable toward and from the path followed by the threader head.

3. The combination with a machine that attaches an eyelet to a sheet article and secures the end of a piece of string to the article by said eyelet, of a threader that delivers the end of string to the region of the eyelet for the connecting operation, and supporting means on which the threader travels about an axis and along a curved path to draw out a length of string after the end is secured to the article by said eyelet, said threader including a radially-extending portion and a head offset from the radially-extending portion in a direction parallel to the axis of the curved path along which the threader travels.

4. Apparatus comprising fastening means for connecting an end of string to an article, a threader having an offset head that moves along a curved path to deliver an end of string to the fastening means and then moves away from said fastening means along the curved path to draw out a length of string, an abutment on the inside of the curved path along which the threader head

travels, an arm by which the abutment is supported, and adjustable means for holding the arm in different positions to locate the abutment in position to be struck by the string when the string has shifted into different chord positions as the threader head travels along its curved path away from the fastening means.

5. The combination with apparatus for attaching an end of string to an article and then cutting the string at a distance from said article, of means for measuring out a predetermined and adjustable length of string that the apparatus will cut off for each article, said means comprising a support that moves an offset threader head of the apparatus along a curved path away from the region where the end of the string is attached to the article, a plurality of arms, pins extending from the arms and across the plane of the curved path that is followed by the threader head and into position to be struck by the string so that the course of the string is held to a broken line comprising a number of chords as the threader head travels along its curved path, supporting means for the arms, and devices for adjusting the arms to change the distance of the pins from the path of the threader head and thus control the length of string included in the total number of said chords.

6. A string-attaching machine including apparatus at a fixed station for fastening the end of a string to an article, a threader that delivers the end of the string to the fastening apparatus and then moves away from the fastening apparatus and back to a fixed location, an abutment about which the string passes and into contact with which the string is drawn by the threader, and adjustable means for changing the position of said abutment and thereby altering the length of string between the fastening apparatus and the threader when the threader is in its retracted location.

7. The combination with apparatus at a fixed station for attaching string to an article, of a threader that carries an end of string into position to be operated upon by said apparatus and then moves away from the attaching apparatus to draw out a length of string, cutting means at a fixed location from the attaching means for cutting off the length of string attached to the article, and measuring means for determining the length of string between the article and the cutting means at the time the string is cut, said measuring means including an arm, an abutment on the arm for contact with the string, and a connection from which said abutment is supported, the connection being adjustable to change the position of the abutment and the resulting length of the string.

8. A machine for connecting predetermined lengths of string to articles, said machine including attaching apparatus that connects a free end of a string to the article while the string is connected to a ball or other source of supply, cutter means for severing the string from the supply source, a threader supported for movement between the attaching apparatus and the cutter means for moving the string to the cutter means, abutment means for determining the length of string between the cutter means and the article at the time the string is severed and means for adjusting said abutment means to change said length of string.

9. A machine for attaching string to articles, said machine including fastening apparatus that secures the string to the article, a threader head

for successively supplying an end of a string to said fastening apparatus, an arm on which the threader head is carried, a shaft by which the arm is supported, operating mechanism for oscillating the arm about the axis of the shaft to shift the threader head along a curved path toward and from the fastening apparatus, a cutter for severing the string near the threader head when the threader head is away from the fastening apparatus, and cam means for moving the threader head with respect to the arm to carry the threader head into an operative relation with the fastening apparatus at one end of each oscillation of the arm.

10. The combination of fastening apparatus for securing an end of a string to a paper or other sheet article, a looper for holding the string while it is acted upon by the fastening apparatus, a threader for delivering the end of the string to the looper and then pulling out a length of string on the return movement, a pivot about which the threader has a limited rocking movement, a shaft, a crank arm angularly movable about the shaft and carrying said pivot near its outer end, operating mechanism for moving the arm angularly about the axis of the shaft as a center, a cam and a cam follower, one of which is relatively fixed and the other of which is car-

ried by the arm and movable with respect to the arm, said cam and cam follower being so disposed that they have relative movement with respect to one another as the arm reaches the end of its oscillation that positions the threader for cooperation with the looper, and motion-transmitting connections carried by the arm and operated by the cam and connected with the threader so that the string-carrying end of the threader moves along a course that departs from a circular arc toward the looper-end of its travel.
